UNITED STATES PATENT OFFICE.

JARED LOCKWOOD, OF NEW YORK, N. Y.

DESIGN FOR A SHIRT-SHIELD.

SPECIFICATION forming part of Design No. 28,439, dated March 29, 1898.

Application filed September 28, 1897. Serial No. 653,382. Term of patent 7 years.

To all whom it may concern:

Be it known that I, JARED LOCKWOOD, a citizen of the United States, and a resident of New York city, in the county and State of New York, have invented a new and original 5 Design for Shirt-Shields, of which the following is a specification.

This invention relates to a design for a shirt-shield adapted for men's wear; and I hereby o declare that this specification, of which the accompanying drawings form a part, is sufficient to enable any one of intelligence to understand and apply my invention.

In Figure 1 of the drawings I have shown 5 a front view of a shirt-shield embodying the invention represented as folded around the neck of the wearer. In Fig. 2 I have shown a top view of the same with the ends extended.

A and A' are the aprons, and B is the neck o portion.

C is a collar formed with and constituting part of the shirt-shield and extending around the neck portion and down each of the aprons. The collar C grows gradually narrower toward its ends and has the general appearance when 25 in use of a soft muffler.

The collar C is the characteristic feature of the design, the same comprising a soft fabric having longitudinal wavy folds or creases c'.

What I claim is—

The design for a shirt-shield having the collar substantially as shown and described.

In testimony whereof I have signed my name to this specification in the presence of two subscribing witnesses.

JARED LOCKWOOD.
